UNITED STATES PATENT OFFICE.

PHILIP HAAS, OF DAYTON, OHIO.

FLUSHING DEVICE FOR WATER-CLOSETS.

1,083,088.

Specification of Letters Patent.

Patented Dec. 30, 1913.

Application filed May 28, 1912. Serial No. 700,337.

To all whom it may concern:

Be it known that I, PHILIP HAAS, citizen of the United States, residing at Dayton, in the county of Montgomery and State of Ohio, have invented certain new and useful Improvements in Flushing Devices for Water-Closets; and I do hereby declare the following to be a full, clear, and exact description of the invention, such as will enable others skilled in the art to which it appertains to make and use the same.

My present invention relates to the class of automatic devices for flushing water closets and consists in an improved construction of valves for controlling the flushing current passing therethrough.

In the drawings I have shown the best form in which I have contemplated embodying my said invention and the same is described in the following description and claims.

In the drawings, Figure 1 is a view in elevation partly in section of my improved valve. Fig. 2 is a horizontal section on line 2—2, Fig. 1. Fig. 3 is a partial vertical section. Fig. 4 is a vertical section on line 4—4, Fig. 1.

In these figures A is the main body or casing in which are the pressure chamber a , the tank chamber a' connected with the tank or reservoir (not shown) the inlet chamber a^2 and the outlet chamber a^3 . The chamber a is closed by a cap A' and the casing is provided with means, comprising in this instance threaded portions, whereby the other chambers can be connected respectively with the water supply, the tank and a pipe leading to the bowl. The pressure chamber is separated from the tank chamber by a partition b^2 and adjacent to the said partition is connected with the outlet chamber by an opening b^3 . The inlet chamber is separated from the tank chamber by a partition b' in which there is an opening b^4 .

Within the chamber a I locate a piston B which has connected therewith either integrally or otherwise a valve B'. To this valve a rod b is secured by a threaded connection and a lock nut b^2 . The outer end of this rod or bar is provided with a valve C. This valve comprises the disk c , the disk c^2 and the diminishing body c' . The periphery of the disk c^2 is provided with cuts or notches c^2 so that water may pass freely from one side of the same to the

other in either direction. The inner face of the disk c constitutes a valve for the purpose of enabling the water pressure to additionally secure the valve opening in the partition b' separating the tank chamber a' and the inlet chamber a^2 . This body of this valve is connected to the disk and valve c and to the rod b and is cut away on three sides, the removed portions diminishing toward the disk c . This valve body is fitted to and works in the opening b^4 of the partition b^2 .

The valve C is normally in position with the disk c seating against the partition b' , cutting off all influx of water from the inlet chamber a^2 and when it is in this position the piston B will be at the opposite or left hand end of the chamber a .

The main body A has upon one side of 75 the same a vertically disposed projection D. This projection is hollowed out to form chambers d , d' connected by a short passage d^2 . Upon the main body there are also two broad webs d^3 , d^4 one on each side of the projection D and connected therewith. The chamber d is closed at its upper end by the cap d^5 . In the chamber d there is located a valve E having an upwardly extending stem e . The upper end of this 85 stem engages the guiding recess d^6 in the cap d^5 . A spring e' around the stem has its upper end bearing against the cap and upon the upper face of a nut e^2 , or upon the upper side of the valve E for moving 90 the valve downward and maintaining it in its lowermost or closed position. Below the valve there is a depending bar or rod d^3 , which may be an extension of the valve stem or a separate device secured to the 95 valve. This rod is of such size as to move freely in the passage d^2 .

The lower end of the chamber d' is closed by a stuffing box through which a rod E' passes and may be moved. Within the 100 chamber d' the rod E' connects with a valve E² adapted to be moved upward and close the lower end of the passage d^2 . The upper end or side of this valve is provided with a pin or short section of rod e^4 which 105 may be a continuation of rod E' or a separate part secured to the valve. This pin e^4 is of such size as to loosely engage a recess d^4 in the lower end of the rod e^3 .

The rod E' is so arranged with reference 110 to the bowl and its seat that pressure upon the seat will, through means not shown,

raise the rod E' and lift the valve E to such an extent as to raise the rod e³ out of the passage d². This movement will also move the valve E² upward and close the 5 lower end of passage d².

By reference to Fig. 2 it will be seen that there is a passage g opening out of the inlet chamber a². This passage is preferably located within the web d⁴ and discharges into 10 the chamber d. In the web d³ is another passage g' connecting the passage d² with the rear or left hand end of the chamber a. The chamber d' is also connected by a short 15 passage g² with the outlet chamber. This raising of the rod E' permits water to flow to through the passage g into the chamber d and from thence into passage d² and through passage g' into the chamber a in rear of the piston B. This moves the connected valve B' 20 to close the opening connecting the pressure chamber and the tank chamber. As the piston begins to move the valve or disk c leaves its seat upon the partition b', permitting water to flow over the reduced portions of 25 the body c' into the tank chamber. This flow is small at first as the current flows first over the higher or larger parts of the reduced portion and gradually increases until the valve B' is seated. The movement 30 of the piston and valve is comparatively rapid and but little water passes from the tank chamber before the valve B' closes the connection of the tank chamber with the outlet. When the valve B' is fully seated it 35 causes the incoming current to flow upward into the tank until the pressure therein equals that of the water supply. When the seat is relieved from pressure the valve E is depressed by the spring e and cuts off the 40 pressure of the water supply upon the piston B and the rod d³ descends into the passage d². This permits the pressure upon the face of the valve B' to force the piston B backwardly and to expel the water in the 45 chamber a out by way of the passage g' through the passage d² around the rod d³ into the chamber d' depressing the valve E² and the rod E'. From the chamber d' the water flows through the passage g² into the 50 outlet. As the valve B' leaves its seat the water from the tank chamber and tank flows out through the opening in partition b' into the chamber a, thence through the opening b³ into the outlet chamber and to the bowl. As the rod e³ so nearly fills the 55 passage d² the outward flow of the water in the pressure chamber is comparatively slow. The greater reduced portions of the body c' of the valve C being in the opening

b⁴ in the partition b² water from the inlet 60 chamber and supply pipe flows out and unites with the current from the tank. The duration of the flow for flushing the bowl depends on the distance between the valve B' and the valve C and this can be increased 65 or diminished by turning the rod b farther out or into the valve B'.

By securing a partial direct flow of water from the supply pipe, I am enabled to make the tank smaller than is usually required, 70 reducing the cost and the space occupied by the device.

When the tank is emptied the flow from the supply pipe is continued decreasing 75 gradually as the valve C moves through the partition b'. As the disk c approaches to close this opening the flow of water will be so far diminished that the siphon action emptying the bowl will cease and only water enough to fill the trap and seal the bowl 80 will flow into the latter, before the disk c will seat itself against the partition b' closing the opening therein. The flow of water will then be entirely cut off and all the parts 85 will have returned to normal position.

What I claim and desire to secure by Letters Patent is:—

In a flushing valve, the combination with a casing provided with a pressure chamber, a tank chamber, an inlet chamber, and an 90 outlet chamber, a partition separating the inlet and tank chambers, a partition separating said pressure and tank chambers, each of said partitions being provided with an aperture therein, and said casing being provided with an aperture connecting the pressure chamber and the outlet chamber, a piston in the pressure chamber, a valve connected therewith for closing the aperture in the adjacent partition, a valve for closing the aperture in the other of said partitions, provided with a part extending through the aperture therein, said part having cutaway portions for gradually diminishing the flow 95 through said aperture before the seating of said valve to restore the water seal, means for establishing a connection from the inlet chamber to the pressure chamber in rear of the piston therein, and adjustable devices positively connecting said valves for 100 determining the duration of the flushing.

In testimony whereof I affix my signature, in the presence of two witnesses.

PHILIP HAAS.
